WIRE DRAWING APPARATUS

George Bryden, Elmwood, Retford, England, assignor to Marshall Richards Machine Company Limited, Crock, England, a British company

Application October 30, 1948, Serial No. 57,535

Claims priority, application Great Britain July 20, 1943

1 Claim. (Cl. 205—14)

This invention relates to a process and apparatus for drawing wire, and more particularly to a multiple die process and apparatus for drawing wire in which a high degree of back tension may be maintained on the wire during the drawing operation, thus making possible higher drawing speeds and reducing substantially the wear on the dies. This application is a continuation-in-part of my application Serial No. 758,546, filed July 2, 1947, now abandoned.

The principle of applying a substantial back tension on wire that is being pulled through a die has been recognized heretofore as having certain advantages because heavy back tension facilitates elongation of the wire and reduction in its diameter as it passes through the die. Theoretically, if sufficient back tension could be applied to the wire to place it under a tension closely approaching its ultimate strength, the work done by the die during drawing would become very slight with little, if any, die friction and die wear.

However, wire is usually drawn commercially in multiple die drawing machines in which the wire is successively reduced by two or more dies arranged in tandem. Heretofore, efforts to draw wire in such multiple die machines involving the application of a high degree of back tension while the wire is moving at high speeds have not been commercially successful. Some machines have been developed for this purpose but have proved to be impractical because of frequent breakage of the wire, excessive scoring of the pulling blocks, or for some other reason.

An object of my invention is to provide a practical, workable process and apparatus by which wire may be drawn successively through a series of dies at a high speed, and with a high degree of back tension on the wire.

A further object of my invention is to provide a process and apparatus of this character in which the wire is under tension from start to finish and such tension may be maintained or controlled regardless of the speed at which the wire is drawn.

Another object is to provide a multiple die wire drawing machine having the foregoing properties and of the simplest construction eliminating the use of idling or jockey pulleys so that the wire is subjected to a minimum of bending and twisting as it passes through the machine.

An additional object of the invention is to provide a multiple die wire drawing machine provided with individual pulling blocks, in which each pulling block is individually driven by a motor, but the motors are so connected that any desired torque relationship may be established between one motor and another and the machine may be speeded up or slowed down without materially disturbing such torque relationship.

Other objects and advantages of my invention will be explained or will be apparent from the following description of the embodiments illustrated in the drawings, in which

Figure 1 is a side elevation showing diagrammatically the principal parts of a four die wire drawing machine

2

and control panel therefor, constructed in accordance with my invention.

Figure 2 is a diagrammatic illustration of a detail of the machine in Fig. 1 showing how a die holder may be constructed and arranged to indicate the amount of pull on an individual die during operation of the machine.

Figure 3 is a wiring diagram showing a preferred manner of connecting the field windings of the motors.

Figure 4 is a wiring diagram showing all of the principal electrical connections for the wire drawing machine illustrated in Fig. 1.

Figure 5 is a diagrammatic showing of a three die machine and its main electrical connections similar to the machine in Fig. 1 but having its motor fields connected in a different manner.

In accordance with my invention, a multiple die wire drawing machine is constructed with individual electric motors driving each capstan or pulling block, and the motors are electrically connected together and to the power supply so that the machine may be threaded up at a slow or creeping speed while maintaining a certain torque relationship from one pulling block to another, and whereby the machine after being threaded up can be brought up to operating speed without breaking the wire and while still maintaining the desired torque relationship between the different pulling blocks.

I have found that a machine constructed according to my preferred embodiment can be operated at exceedingly high speeds, greatly above those commercially available heretofore. At the same time the die friction and resultant die wear are materially reduced, the quality and uniformity of the drawn wire are improved, and the machine may even be operated at somewhat smaller total power consumption than has been required heretofore.

Figure 1 illustrates somewhat diagrammatically a preferred form of multiple die wire drawing machine constructed in accordance with my invention in which wire is successively pulled through a series of dies 1, 2, 3 and 4 arranged in tandem. Capstans or pulling blocks 5, 6, 7 and 8 are also mounted on the bed 9 of the machine in a position to pull the wire straight through each of the dies, one such pulling block being associated with each die. The pulling blocks are preferably individually driven by the motors 10, 11, 12 and 13 through suitable reduction gearing such as a worm and worm wheel. It will be observed in the machine illustrated in Figure 1 that the dies and blocks are mounted so that the wire leaving each die is pulled in a straight line from the die by its pulling block, and that the wire, after passing a suitable number of turns around such pulling block, is passed in a straight line to the entering side of the next die. Thus, the wire in passing through the entire machine moves in a straight path except for the turns or wraps of the wire about each of the pulling blocks. By arranging the blocks and dies, except for the finishing block, in a tilted position, the machine may be constructed so that all of the blocks are at approximately the same heights above the floor level. If desired, however, the same straight path for the wire may be achieved by mounting each successive die and pulling block at a higher level than the previous ones to form a series of steps and maintain the wire in a horizontal path of travel throughout the machine.

A control panel 14 for the machine is preferably located in a convenient position and provided with a number of electrical or other indicators and controls. While not essential, one very desirable and convenient indicator for such a control panel is a die pull indicator, four of which are shown at 15, one being provided for each die.

Figure 2 illustrates diagrammatically one suitable way in which these indicators and dies may be constructed and connected, although any suitable device may be used

which indicates to the operator the amount of pull required at any given instant to pull the wire through the die. As illustrated, this device includes a die holder 16 pivotally mounted at 17, and carrying a suitable wire drawing die 18. The lower end of the die holder 16 preferably carries a block which bears against a torus or annulus 19 of hollow, flexible material such as rubber tubing filled with a suitable fluid such as oil. The annulus 19 is pressed by the die holder 16 against a portion of the frame 20 as the wire 21 is pulled through the die 18. The indicator 15 for the die may consist of any suitable type of pressure gauge such as a Bourdon tube arranged to operate an indicating needle or hand and connected by a small tube or pipe 22 to the interior of the annulus 19. Thus, as will be understood by those skilled in the art, the indicator 15 at any given moment registers with its needle the amount of pressure on the annulus 19 produced by the pull of the wire 20 on the die 18. The die holder indicators 15 may easily be calibrated to register die pull in pounds or other suitable units. For operating purposes, it may also be desirable to provide the faces of the indicators 15 with separate manually adjustable hands which can be moved to any given position.

Figure 4 illustrates the principal electrical connections for a machine constructed in accordance with my preferred embodiment. For reasons which will be explained, the motors 10, 11, 12 and 13 are preferably D. C. motors, and have their armatures 23, 24, 25 and 26 connected in series to the power supply line 27. In this manner, the current flowing through the different armatures is always the same in each motor.

An ammeter 28 may be connected in series with the armatures and conveniently located on the control panel 14 to indicate the amount of total current being used by the machine at any time. To facilitate starting and threading up the machine, a large bank of resistors or a large variable resistor 29 is preferably also connected in series with the motor armatures.

The resistance 29 may be provided with a control handle on the control panel 14, if desired, although I prefer to utilize controls on the machine itself. For example, a bar extending along the base of the machine may be so connected that the operator can adjust the resistance in series with the motor armatures, at least in part, from any position in front of the machine by simply pressing one of the foot treadles 29a. This makes it easier for one man to thread up the entire apparatus.

The main field windings 30, 31, 32 and 33 of the motors are preferably separately connected to the power lines 27, each such field winding being connected across or in parallel with the power lines, and each such field winding being connected in series with a pair of separately adjustable rheostats as indicated at 34, 35, 36 and 37, and at 34a, 35a, 36a and 37a, respectively. The first mentioned set of these individual field rheostats may be mounted on the control panel 14 so that they can be adjusted by the handles 38, 39, 40 and 41, respectively, and are arranged to be short circuited by closing the shunt switches 34b, 35b, 36b and 37b, respectively. The second mentioned set of these individual field rheostats may be adjusted by operation of the control handles 34c, 35c, 36c and 37c, respectively, located in convenient positions on the machine itself.

In addition, a large or main rheostat 42 is preferably connected in series with all of the fields and the main power lines so that the field strengths of all the motors may be adjusted simultaneously to alter the speed of the entire machine. This main speed regulating rheostat may also be mounted on the control panel and provided with an operating handle as shown at 43.

While not absolutely essential, it is most desirable in order to simplify operation of the machine as it is speeded up or slowed down, to design the individual motors so that the relative torque produced by each is substantially independent of the total load on the machine.

When the motor armatures are connected in series as shown at Fig. 4, this may be achieved easily by building into each motor a suitable small compound field winding 44, in series with the armature, so that the effective field strengths of the motors are substantially independent of the magnitude of the armature current.

If desired, ammeters 45, 46, 47 and 48 connected in series with each motor's main field may be employed and calibrated to furnish an indication on the control panel 14 of the amount of torque developed by each motor in relation to the armature current shown by the ammeter 28.

In order to indicate the manner in which the total load of the machine is shared by the different motors, voltmeters 50, 51, 52 and 53 may be connected across each armature and arranged to furnish this information on the control panel. Some means is also very desirable to prevent excessive speed of one or more motors in the event the wire should break at any stage. For this purpose, any well-known form of over-voltage relay may be provided for interrupting the main power supply whenever the voltage across any one armature exceeds a safe value. The coils for such over-voltage relays are indicated across each armature at 54. If desired, the control panel (Fig. 1) may also be equipped with any well-known form of speed indicator 55 showing the speed at which the wire is moving as it leaves the last die 4.

This machine may be threaded up and operated as follows:

Before the machine is started, the resistance 29 is adjusted to a position in which resistance is all, or substantially all, in series with the motor armatures. The switches 34b, 35b, 36b and 37b are all closed thus short circuiting the rheostats 34, 35, 36 and 37. The control handles 34c, 35c, 36c and 37c are turned to a position such that the rheostats 34a, 35a, 36a and 37a are in open circuit position so that the circuits through the fields of all the motors are open. The rheostat 42 is adjusted to a position in which it does not introduce any resistance into the circuit.

The rod or wire to be drawn is now pointed, passed through die 1 and attached to the block 5 in the usual manner. The operator then presses on one of the foot treadles 29a to cut out some of the resistance 29 and turns handle 34c until the first block 5 begins to revolve slowly. After a sufficient number of turns or wraps of the wire have been built up on the pulling block 5, the handle 34c is turned back toward the starting position until the amount of the resistance 34a in the field circuit of motor 10 is such that the motor stalls but still maintains the wire under a substantial tension. The foot treadle 29a may then be released to increase the amount of resistance 29 in the armature circuit, and while the first motor is in this stalled condition, the wire on the block 5 is secured firmly in place with a suitable clamp, wedge or similar device.

The end of the wire which is left free is then repointed, passed through die 2 and secured to pulling block 6 in the same manner as previously described. Foot treadle 29a is then again depressed, and control handle 35c is turned to close the field circuit of motor 11 and adjusted until pulling block 6 just starts to rotate. Pulling block 6 turns until the slack between die 2 and pulling block 5 is taken up, at which point the motor 11 is allowed to stall long enough to remove the clamp on pulling block 5. The handle 35c is then turned still further to reduce the resistance in the field 31 of motor 11, until both the pulling blocks 5 and 6 begin to rotate slowly. They are allowed to rotate in this manner until a sufficient number of turns or wraps of wire are built up on pulling block 6 when the control handle 35c is backed off to the stalling condition for motors 10 and 11. Foot treadle 29a is then released to increase resistance 29, and a clamp is again applied to the wire on pulling block 6.

The wire is again pointed and the same operation is performed to start the wire through dies 3 and 4 and

build up an adequate number of turns or wraps on the pulling blocks 7 and 8. The end of the wire is firmly secured to the final or finishing block 8.

It will be apparent from the foregoing description that at this stage the pulling blocks 5, 6 and 7 do not exert sufficient pull to pull the wire through the preceding dies without the assistance of the torque applied by motor 13 to the finishing block 8. Thus, the wire between the pulling blocks 5, 6 and 7 and the dies 2, 3 and 4, respectively, is under a substantial amount of tension. This tension applies back tension on the wire entering these dies and at the same time exerts a forward pull to assist in driving the pulling blocks 5, 6 and 7.

The machine is now ready to be brought up to operating speed. To accomplish this, the rheostats 29 and 42 are adjusted or operated so that the resistance 29 in the armature circuit is reduced to zero and the resistance 42 in the field circuit is increased to a point necessary to run the machine at the desired speed.

The rheostats 34, 35, 36 and 37, which up to this time have been short circuited, are introduced into the field circuits after the machine has started to accelerate by opening the switches 34b, 35b, 36b and 37b. This may be done after the machine reaches its operating speed or at some point before it reaches such speed. The introduction of the rheostats 34, 35, 36, and 37 into the motor field circuits varies the amount of torque applied by each motor relative to the other motors depending upon the settings for these rheostats at the time the shunting switches are open.

If the settings for these field rheostats have not been predetermined, they may be manually adjusted by the operator after the machine is up to speed to produce the desired back tensions on the wire on each of the dies 2, 3 and 4. In making such adjustments, the operator is guided by the die pull indicators 15, which show a decrease in die pull as the back tension is increased, and by the other instruments on the control panel.

On the other hand, if the desired settings of the field rheostats are known for a particular operation, the controls 38, 39, 40 and 41 may be properly pre-set before the shunting switches 34b, 35b, 36b and 37b are opened.

The manually adjustable hands on the die pull indicators 15, which were previously mentioned, may be adjusted before the machine is threaded up, or during the process of threading up, to indicate the natural or normal amount of die pull at each die when the wire is being pulled through the die without any back tension on the wire entering the die. In this manner, the operator can determine readily the difference in the amount of die pull while the machine is operating with back tension on the wire by noting the relative positions of the fixed manually adjustable hands and the indicating hands on the die pull indicators 15.

The connection of the armatures of the motors in series provides a speed control and permits a torque control which meets the particular needs of a multiple die non-slip continuous wire drawing machine. In such a machine, the pulling blocks are, in effect, geared together by the wire so that the relative speeds of the motors are determined by the reduction in area of the wire at each die. With the series connected armatures, the individual motor speeds are completely self-adjusting to the die reductions, and the sum of the motor speeds can be controlled by rheostat 42.

The torques of the individual motors connected together in accordance with my invention may be separately adjusted as previously described to provide the desired heavy back tensions at the different dies. Furthermore, once the relative torque adjustments are made, they remain substantially undisturbed by the operation of the machine at different speed levels.

These characteristics permit such a machine to be threaded up at very slow or creeping speed, and then brought up to operating speed without breaking the wire.

In fact, the motors may even be stalled during this operation. In addition, this machine permits unusually wide variations in the percentage reductions that may be made in the wire at individual dies.

The wire passing through the machine is also subjected to a minimum of bending and is tight at all points without any slack. This not only permits high operating speeds in the drawing operation, but also prevents circumferential slippage of the wire on the drawing blocks with its attendant wear or scoring of the blocks. With no slippage of the wire on the pulling blocks, a larger than usual number of turns or wraps of the wire may be taken around each block, thus giving more opportunity to cool the wire between dies. The blocks may be cooled by water or air, or both, for this purpose.

By "no slippage" is meant no circumferential slippage of the wire around the blocks except for a negligible amount of diagonal slip as the coil is pushed up the block by the oncoming wire, an amount which may be disregarded for all practical purposes.

Another advantage of a wire drawing machine constructed according to my invention is that it may be provided with a spooling device driven by a motor connected into the electrical circuits in a manner similar to the connection of the motors driving the pulling blocks.

Figure 3 shows in its simplest form the parallel connection of three of the motor fields to the power supply 27. This involves the same type of circuit as illustrated in Fig. 4 in which separate rheostats 34, 35 and 36 are provided for each field and the main variable resistance or rheostat 42 is connected in series with all of the fields to enable the machine to be operated at very slow speeds or to be brought up to full operating speed without disturbing the individual torque relationship between the motors.

An alternative arrangement for connecting the motor fields is illustrated in Fig. 5, in which the dies 1, 2 and 3 are shown diagrammatically for drawing the wire 21, the wire being pulled through the dies by the pulling blocks 5, 6 and 7. Each pulling block is driven through reduction gearing 10a, 11a and 12a by the individual motors whose armatures are indicated at 23, 24 and 25. In this case, the armatures may be series connected as previously described in connection with Fig. 4. The motor fields 60, 61 and 62, however, are shown as connected in series to the power supply 27, each field being provided with taps 63, so that the individual field strengths of the motors can be adjusted separately to vary the field strengths of the motors and thereby the torque relationship of the motors. Here again, the main field rheostat 42 is connected in series with the fields and power supply to adjust the operating speeds of the motors simultaneously. This alternative arrangement of field connections can be used, although I prefer to connect the fields in parallel as previously described since this avoids the necessity of using taps on the motor fields.

While resistors have been described as the means for controlling the armature and field currents, especially for starting the machine, or applying stalled tension during threading up, it will be apparent to those skilled in the art that a similar result may be achieved by other variable voltage supply means such as grid controlled gaseous rectifiers or by a Ward Leonard type of motor driven generator with field control.

The invention has been described in connection with an embodiment that involves the use of direct current motors, since motors of this type are easily designed and connected to provide the independent torque and speed adjustments which are necessary in the operation of my machine in order to produce satisfactory high speed drawing of the wire under considerable back tension. It is possible, however, to use alternating current motors provided they are so constructed and designed as to be capable of connection to each other and to the power supply, either directly, or through the use of transformers or other control equipment, to provide the necessary in-

7
dividual torque adjustability and to provide also the necessary speed adjustment without materially disturbing the torque relationship between them. Wound-rotor induction motors, for example, might be used in place of the direct current motors which at this time I prefer.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

A multiple die wire drawing machine comprising a plurality of dies and pulling blocks alternately arranged so that the wire passes directly from a die to its pulling block and thence to the next die, separate direct current electrical motors for driving each block, said motors being constructed so that their field strengths are substantially independent of their armature currents and being connected with their armatures in series and their fields in parallel with a power supply, rheostats con-

5
nected to each motor field circuit for varying the individual field strengths of the motors relative to each other, and means for increasing or decreasing the speeds of all motors simultaneously.
